UNITED STATES PATENT OFFICE.

LOUIS PHILIP LANDRY, OF WOONSOCKET, RHODE ISLAND.

STOP MOTION FOR LOOMS.

Application filed September 22, 1923. Serial No. 664,291.

My present invention pertains to means for detecting broken loom harness operating connections and the actuating thereby of the loom stop motion.

5 In order to enable those skilled in the art to appreciate my improvements I deem it necessary before entering into a detail description of the invention to refer to certain elements (not illustrated) of a loom. By 10 reference to the construction of a loom and more particularly to worsted looms it will be manifest that the harness is actuated by means of straps and other connections. These connections are secured to both the 15 top and bottom of the harness; the ones at the top being to elevate and support the harness in such position and the attachments at the bottom are to permit fall of the harness when they are released by the top connections. 20 The lower connections, at certain points, are permitted to pass under rollers or the like whereby their direction of movement is changed to the horizontal from the perpendicular, and generally this direction 25 is parallel with the lay and harness; intermediate these rollers and the actuating means, the connections are constructed of wire as indicated by 13 in Figure 1. Those conversant with looms are well aware of 30 the fact that between the actuating means and the harness of the looms there are provided connections. I do not deem it necessary to illustrate a loom together with the harness but merely show the connections or 35 wires 13. During the operation of a loom it frequently happens that some portion of the harness operating connections will break causing the harness operated therefrom to remain inoperative. In view of the fact 40 that the pattern of cloth on the loom is directly dependent upon the steady operation of each harness it is very evident that when the breakage takes place it is manifestly important that the loom be stopped, 45 and thereby prevent weaving of imperfect fabric.

Because the wires 13 are secured and hold under tension the harness any damage to the harness will naturally cause the connection to sag which in turn will bear upon the arm 11 forcing said arm downwardly.

It is the purpose of my improvements to not only overcome the objections set forth but also to immediately detect the breaking 55 of the harness in order to actuate the stopping mechanism of the loom.

The invention in all of its details will be fully understood from the following description and claims when the same are read in connection with the drawings accompanying 60 and forming part of this specification, in which:

Figure 1 is a perspective view showing my novel means for detecting broken harness. 65

Figure 2 is a view of the side of the device and illustrated at right angles to the lay, harness, etc. of a loom.

Figure 3 is a sectional view showing in detail certain elements of the detecting 70 means.

Similar numerals of reference designate corresponding parts in all the views of the drawings.

Secured to some convenient portion on 75 the loom frame, for instance, on a cross-brace 3 is a bracket 2 which supports a vertical plate 5 and supported therefrom is a pin 7 that in turn receives a swinging lever 6, and supported by this lever 6 is an arm 11 having the upstanding portion 12, and 80 said arm 11 is preferably of stiff wire or other comparatively light material and is adjustably secured in the lever 6 by means of a thumbscrew 10 or other suitable means 85 that may suggest itself. The arm 11 is suspended so as to bear lightly upon each of the wires 13 that in turn are connected with the harness of a loom and in such a manner that when not held taut the wires 90 13 will bear against the arm 11.

As clearly shown in Figures 1 and 2 a post 15 is attached to the plate 5 and this post is insulated therefrom at the point 17 by insulating material. This post is positioned to engage the arm 8 of the lever 6 when same is operated upon by a supporting pin 7 which serves as a fulcrum if the harness breaks or the supports thereof get out 100 of place.

Any means may be employed to retain the lever 6 in a position as shown out of engagement with the post 15 such for instance the flat spring 14 but in this connection, I would have it understood that the tension on the arm 8 is normally retained to keep it in the position shown in Figure 2.

The dotted line shown in Figure 2 by the dotted lead line 18 illustrates the circuit or wire in the conduit which is used in connection with the post 15 and may be located 105 and supported in any approved manner and 110

the remaining conduit for forming the electric power is provided through the loom frame 3 that supports the arm 1 and the arm 11 of the lever 6; the circuit being completed when the lever 8 is operated so that the arm 8 forms the contact with the post 15.

The harnesses are connected to cords (not shown) at the top thereof, and these cords 10 operate over pulleys that are secured to the top of the frame. The vertical cords 21 are connected to the lower end of the harnesses and operate over pulleys 22 secured to the lower end of the frame. The cords 21 terminate in the wires 13, hence if the cords 21 or the connections thereof break and cause the harness to drop, the wires 13 will sag sufficiently to operate the stop motion mechanism.

20 The reason for the circular portion 4 is to protect the post 15 and arm 8 and prevent lint flying from the loom lodging on same with the liability of causing fire.

In the practical operation of the device, 25 when one of the harness operating connections break, either the top or bottom ones; should it for instance be the top one the harness will be allowed to fall and by so doing the lower connection of same will be caused to sag and its weight will be imposed upon the arm 11 resulting in actuation of the member 8, thereby elevating said arm or member 8 until it engages the post 15 causing the electric circuit to close and thereby 30 operating the shipping mechanism of the loom (not illustrated). Many looms are provided with electrically operated shipping mechanism to cause stopping of the loom.

35 40 It will be manifest from the foregoing, that the invention is simple in operation and

inexpensive to produce and comprises no delicate parts such as are liable to become inoperative after a short period of use.

The device is positive in operation and 45 may be easily installed on looms at present in use and assures not only great saving in harness mechanism but also reduces the liability of weaving cloth or the like in an imperfect manner and thus necessitate the 50 discarding of a large amount of the finished product because of its imperfect condition.

The connecting wires 13 bear on the arm 11 and run from the harness to the actuating mechanism of a loom and manifestly 55 if any of the elements arranged in communication with the harness or the harness itself breaks or otherwise get out of position, the harness will sag causing its complementary wire 13 to sag which in turn will bear 60 down on the wire thereby forcing same against the arm.

Having described my invention, what I claim and desire to secure by Letters-Patent is:

In means for the purpose set forth, the combination with a loom, wires adjacent the loom, and intermediate the harness and actuating mechanism of the loom a bracket secured to the loom frame and having a hood-shaped portion formed at one end thereof, a plate formed integral on the bracket, a post arranged on the plate, a tension arm mounted on the plate within the hood-shaped portion, an arm that rests below the wires and 70 is secured to the tension arm whereby movement of the tension arm will close a circuit that communicates with the post and shipping mechanism of the loom.

In testimony whereof I have hereunto set 75 my hand.

LOUIS PHILIP LANDRY.
